CLAIM

The ornamental design for a computer input device, as shown and described.

DESCRIPTION

FIG. 1 is a perspective view of a computer input device showing the new design;

FIG. 2 is a side elevation view thereof;

FIG. 3 is a front elevation view thereof; and,

FIG. 4 is a top elevation view thereof.

1 Claim, 4 Drawing Sheets

FIG. 1

FIG. 2

FIG. 3

FIG. 4
